(57) CLAIM

I claim the ornamental design for a footwear upper portion,
as shown and described.

DESCRIPTION

FIG. 1 is a perspective view, from the front and right side,
of a footwear upper portion, showing my new design;

FIG. 2 is a right side view thereof;

FIG. 3 is a left side view thereof;

FIG. 4 is a front end view thereof; and,

FIG. 5 is a rear end view thereof.

The broken line showing in the figures of a sole, a lower part
of the upper, and tightening elements on the upper is for
illustrative purposes only and forms no part of the claimed
design.
